UNITED STATES PATENT OFFICE.

GEORGE J. GEISSE, OF HELENA, MONTANA.

FLUSHING DEVICE FOR TOILETS.

1,403,762.

Specification of Letters Patent. Patented Jan. 17, 1922.

Application filed May 28, 1921. Serial No. 473,549.

To all whom it may concern:

Be it known that I, GEORGE J. GEISSE, a citizen of the United States, residing at Helena, in the county of Lewis and Clark 5 and State of Montana, have invented certain new and useful Improvements in Flushing Devices for Toilets, of which the following is a specification.

My invention relates to a flushing device 10 for toilets.

The objects of the invention are to provide a flushing device which will dispense with the employment of the ordinary reservoir or tank; to provide means for supplying a predetermined amount of water to the 15 toilet, and automatically cutting off such supply; to provide a device of the above mentioned character adapted to be directly connected with the water main, to receive 20 water therefrom at the pressure in the main; to provide a device of the above mentioned character, which is neat in appearance, highly sanitary, and will take up very little 25 space in use; to provide a device of the above mentioned character, which is strong, durable, and inexpensive to operate and retain 30 in repair; to provide a device of the above mentioned character which is not liable to derangements, and in which the outlet valve 35 is so arranged that it may be quickly and conveniently removed, for applying new packing thereto when desired.

Other objects and advantages of the invention will be apparent during the course 40 of the following description.

In the accompanying drawings forming a part of this specification, and in which like numerals are employed to designate like parts throughout the same,

Fig. 1 is a side elevation of a device embodying my invention, parts being removed, and parts broken away, for the purpose of 45 illustration,

Fig. 2 is a transverse section taken on line 2-2 of Figure 1, and,

Fig. 3 is a detail section taken on line 3-3 of Figure 1.

In the drawings, wherein for the purpose 50 of illustration is shown a preferred embodiment of my invention, the numeral 5 designates a main casing, which may be formed of metal or the like. This main casing is supported by any suitable means, in proximity to the bowl of the toilet. One side of

the casing 5 is closed by a cover 6, secured thereto by screws 7 or the like.

Preferably formed integral with the upper portion of the casing 5 is a water wheel casing 8, which is preferably circular, and projects above the same. One side of this 60 casing 8 is open and is closed by a cover 9, secured thereto by screws 10 or the like.

The numeral 12 designates a water wheel, rigidly mounted upon a horizontal transverse drive shaft 13, journaled in bearings 65 14 and 15. A cap 16 is preferably secured to the cover 9, and may be equipped with a small grease cup 17, to lubricate the bearing 14. The numeral 18 designates a packing collar or the like, to prevent the leakage of 70 water from the bearing 15. Arranged within the casing 5 is a driving gear 19, rigidly mounted upon the end of the shaft 13, and engaging a tripping gear 20, of larger diameter, which is rigidly mounted upon a horizontal driving shaft 21. This shaft 21 is rotatably held in a bearing 22. The gear 20 carries a laterally extending trip 23, as shown.

Arranged within the bottom of the casing 80 5 is an outlet or flushing valve casing 24, the outlet end of which is connected with a pipe 25, leading to the bowl, while its inlet end is connected with a pipe 26, extending upwardly for connection with the outlet 27 of 85 the water wheel casing 8. The valve casing 24 has an annular valve seat 28, to be engaged by a packing ring 29, carried upon a valve head 30. This valve head is preferably detachably mounted upon the lower end 90 of a valve stem 31, and is adapted to be removed through the opening of a removable valve plug 32. The valve head 30 seats upwardly against the valve seat 28, and the valve stem 31 is moved upwardly by a spring 95 33, engaging a yoke 34, carried by the valve stem, with or without the assistance of the water pressure beneath the valve head 30.

The yoke 34 has pivotal connection at 35, with a vertically swinging lever 36, operating 100 through a slot 37. The rear end of this lever is pivoted at 38. The lever 36 is adapted to be locked in the depressed position by means of a weighted lock element 39, having a locking face 40 and releasing face 41. The 105 locking element 39 is pivoted to swing in a vertical plane, at 42, and carries a finger or extension 43, arranged in the path of travel

of the trip 23. It is obvious that the pivot 42 of the locking element 39, is so located, that the rear or locking end 40 of the element will automatically gravitate to the lowered position, Fig. 1, when released.

The numeral 44 designates a water supply pipe, having a valve 45 connected thereto, to regulate the supply of water to the device, at the desired pressure. The pipe 45 leads into an inlet 46 of the water wheel casing 8, preferably at its top, at a tangent.

In operation, when the lever 36 is elevated, it engages releasing face 41 of the locking element 39, thereby holding element 39 against turning movement. The valve stem 31 is now elevated and valve 30 seated. To flush the bowl, the lever 36 is depressed, and the locking element 39 will then swing downwardly upon its pivot 42, its locking face 40 now engaging the lever 36 and holding it depressed. The valve 30 is now opened and the water will discharge through the device and enter the pipe 25. As the water passes through the water wheel casing 8, it rotates the water wheel 12 in the direction of its arrow, and the tripping gear 20 is accordingly rotated in an opposite direction, as indicated by its arrow. When the gear 20 has made substantially a complete revolution, the trip 23 will engage the finger 43, and swing the locking element 39 upwardly, the spring 33 then closing the valve 30 and swinging the lever 36 upwardly to engage the holding face 41, the locking element 39 being now held in the raised position. The trip 23 is carried past the finger 43, before the water wheel is brought to rest, and hence will not interfere with the swinging movement of the finger 43, when the lever 36 is again depressed.

It is to be understood that the form of my invention herewith shown and described, is to be taken as a preferred example of the same, and that various changes in the shape, size and arrangement of parts may be resorted to without departing from the spirit of my invention or the scope of the subjoined claims.

Having thus described my invention, I claim:

1. In a flushing device of the character described, a water supply conduit, a water wheel casing connected therein, a water wheel within said casing, a valve casing connected in said conduit, a valve head mounted within the valve casing and seating upwardly, a valve stem connected with the valve head and extending upwardly, a spring to move the valve stem upwardly, a vertically swinging lever connected with the valve stem and adapted to move it, a weighted pivoted locking element arranged

above said lever and having a forward locking face and a releasing face disposed at an angle to the locking face, said locking element having an extension, and a member driven by the paddle wheel and carrying a trip arranged to engage said extension.

2. In a flushing device of the character described, a water supply conduit, a water wheel casing connected therewith, a water wheel within said casing, a valve casing connected with said conduit, a valve head mounted within the valve casing and seating upwardly, a valve stem connected with the valve head and extending upwardly, a spring tending to move the valve stem upwardly, a vertically swinging lever pivotally connected with the valve stem, a weighted locking element having its forward end adapted to swing downwardly when released, the locking element being provided at its forward end with a locking face and having a releasing face upon one side, both faces being adapted to engage said lever, a wheel driven by the water wheel, and a trip carried by the wheel and adapted to engage the locking element.

3. In a flushing device of the character described, a water supply conduit, a valve casing connected therein, a valve head within the casing, an upwardly extending valve stem connected with the valve head, a vertically swinging lever connected with the valve stem, a gravity operated locking element pivotally mounted near and above the lever to engage therewith when the lever is elevated and to automatically lock the lever in the lowered position when depressed, and means operated by the passage of water through the conduit to trip the locking element to release the lever to permit the same to move upwardly.

4. In a flushing device of the character described, a water supply conduit, a valve casing connected therein, a valve head within the casing, an upwardly extending valve stem connected with the valve head, means to move the valve stem upwardly, a vertically swinging lever connected with the valve stem, a pivoted locking element arranged above the lever and having one end weighted to automatically descend when the locking element is released, said lever when elevated serving to hold the locking element against downward swinging movement, and the locking element holding the lever depressed when the lever is shifted downwardly, and means operated by the passage of the water through the conduit to trip the locking element and return the same to the elevated position.

In testimony whereof I affix my signature.
GEORGE J. GEISSE.
